(57) **CLAIM**

I claim the ornamental design for a surgical clamp, as shown and described.

DESCRIPTION

FIG. 1 is a perspective view of a surgical clamp according to a first embodiment of my new design;

FIG. 2 is a top view thereof;

FIG. 3 is a bottom view thereof;

FIG. 4 is a right side view thereof;

FIG. 5 is a left side view thereof;

FIG. 6 is a rear view thereof;

FIG. 7 is a front view thereof;

FIG. 8 is a perspective view thereof with the arms of the clamp in an open position;

FIG. 9 is another perspective view of a surgical clamp according to a second embodiment of my new design;

FIG. 10 is a top view thereof;

FIG. 11 is a bottom view thereof;

FIG. 12 is a right side view thereof;

FIG. 13 is a left side view thereof;

FIG. 14 is a rear view thereof;

FIG. 15 is a front view thereof; and,

FIG. 16 is a perspective view thereof with the arms of the clamp in an open position.
